[57] CLAIM

The ornamental design for a telephone, substantially as shown and described.

DESCRIPTION

FIG. 1 is a perspective view from above and to one side of a telephone showing our new design; the telephone cord is understood to continue uniformly throughout the broken line area of the several views;

FIG. 2 is a top plan view thereof;

FIG. 3 is a front elevational view thereof;

FIG. 4 is a left side view thereof;

FIG. 5 is a right side view thereof;

FIG. 6 is a rear elevational view thereof;

FIG. 7 is a bottom view thereof; and

FIG. 8 is a perspective view thereof with the handset of the telephone being displaced.

FIG. 1

FIG. 2
